UNITED STATES PATENT OFFICE

WILLIAM C. HAYMAN, OF SCHENECTADY, NEW YORK, ASSIGNOR TO GENERAL ELECTRIC COMPANY, A CORPORATION OF NEW YORK

THREE-CONDUCTOR CABLE

Application filed August 25, 1928. Serial No. 302,091.

The present invention relates to the type of electric cable comprising multiple conductors, each of which is suitably insulated, an enclosing sheath and a passage or channel 5 inside the sheath for fluid insulation, such as oil, which fluid impregnates the insulation.

The object of my invention is to provide a cable of the above mentioned type which is 10 of improved construction, particularly with respect to the means which form the fluid passages or channels.

For a consideration of what I believe to be new and my invention, attention is directed 15 to the accompanying description and the claims appended thereto.

In the drawing which is illustrative of my invention, Fig. 1 is a cross-section of a cable; Fig. 2 is a short length of cable, and 20 Fig. 3 is a detail view of one of the oil channels.

4 indicates the conductors of which three are shown spaced 120° apart about a common center. They are shown as being of the 25 sector type or shape which has the advantage among other things of permitting a somewhat greater amount of metal, such as copper, for a given diameter of sheath than where they are circular in cross-section. Also the arrangement decreases the liability of crushing of the cable sheath in reeling and installing. I may, however, utilize conductors which are differently shaped in cross-section. 30 Each conductor is tightly wrapped with paper or equivalent insulation 5. Outside of the insulation is a tightly wrapped or metal or metalized body 6 which in the present instance comprises a thin metal ribbon which has numerous and usually equally spaced 35 40 holes or perforations 7 and through which oil is free to pass and permeate the insulation. The ribbon on each conductor is in electrical and mechanical contact with those on the other conductors and is also in electrical communication with the outer casing or sheath 8. These ribbons serve to distribute the electrical stresses and also serve to convey heat from the inside of the cable to the 45 sheath. It is desirable to space the turns 50 one from the other by a slight amount so as

not to impede the free passage of oil to and from the paper. It is also desirable to so arrange the perforations that the resistance to flow of current is the same in all directions. This is done by making the perforations of the same size and spacing them equally. The conductors are laid up in such a way as to form long pitch spirals as is customary in cable construction. The conductors are tightly bound together by a thin strip of metal 9 which to distinguish it from the perforated ribbon or metalized bodies will be called a tape. The tape in addition to preventing the conductors from spreading due to any cause, such for example as heavy load conditions or bending of the cable in reeling and in installing, establishes electrical connections between the perforated ribbons and the sheath 8.

In the construction thus far described there are three spaces or channels 10 which are located one hundred and twenty degrees apart and also one in the center where the ribbons do not make contact, for the reception of oil. In each of the outer spaces is located a metal tube 11 which forms an oil channel or passage, said tubes being spirally arranged, following in this particular the lay of the cable conductors. These tubes also serve the important function of preventing the collapse of the lead sheath 8 due to any cause. In addition these tubes must be so constructed as to permit oil to freely pass from them into the spaces in which they are located. Moreover, they must be flexible in order not to interfere with the bending of the cable, or on the other hand be crushed or deformed by such bending. Lastly and which is the most important feature of all from a manufacturing point of view they must be of such a character as not to change in diameter due to elongation or otherwise as they are fed into place from bobbins or other supports in the cabling machines, meaning thereby the machines in which the several conductors and their coverings are stranded or formed into a cable.

A form of tubing which has all of these necessary and desirable qualities is illustrated in Fig. 3. This tubing is formed from a rela-

tively thin strip of metal 12, say of the order of 10 to 15 mils in thickness, which is wound in spiral form with interlocked edges by suitable dies. As finally shaped each turn has a portion 13 of large diameter and another portion 14 of smaller diameter the latter interlocking with the portion of larger diameter of the adjacent turn. The larger portion of each turn has an internal shoulder 15 which interlocks with an external shoulder 16 on the portion of smaller diameter of the adjacent turn. These interlocking shoulders prevent the tube from elongating in the cabling operation and hence prevent reduction in diameter due to that cause. The portions 13 are of arched construction and due to this and to the interlocking shoulders offer great resistance to crushing or deforming strains which strains if great enough to crush the tube would decrease the diameter of its bore, interfere with the flow of oil and deform the cable as a whole. For the metal strip I may in some cases use a non-magnetic metal, such as copper, zinc or aluminum, while in other cases I may use a magnetic metal such as iron or steel. When magnetic material is used the insulations on the conductors should be covered with shielding means such as the perforated ribbon or equivalent metalized 30 surface.

Such a tube can be bent at a considerably smaller angle than the cable itself, is very strong, and while the turns engage one another and are reasonably tight fitting oil will readily pass through the joints into the surrounding spaces from which it is free to enter the insulation on the conductors and also the central space between the conductor coverings.

40 In addition to the features above enumerated the tubes are good conductors of heat picking it up from the perforated ribbons around the conductors and from the oil and conveying it to the surrounding steel tape from which the heat passes directly to and through the sheath. The fact that after the steel tape is tightly wound over the conductors and tubes the structure thus formed is not truly cylindrical but is slightly flattened 45 in the space between each tube and the adjoined conductor coverings has the advantage that the tape contacts with the tube over a considerable area and in this manner improves the heat conductivity of the parts.

55 What I claim as new and desire to secure by Letters Patent of the United States, is:

1. In an electric cable, the combination of a number of insulated conductors arranged about a common center, an enclosing sheath, 60 there being spaces between each pair of conductors and the inner wall of the sheath, and flexible metal tubes, each comprising a spirally wound strip of metal having overlapping edges to prevent crushing, located in said 65 spaces which supply fluid insulation to the

spaces and to the insulation on the conductors and which also cooperate with the conductors to support the sheath.

2. In an electric cable, the combination of a number of insulated conductors arranged about a common center with peripheral spaces between them, a shielding means for each conductor which distributes electrical stresses, flexible metal tubes, each comprising a spirally wound strip of metal having overlapping edges to prevent crushing, located in said spaces and which convey fluid insulation thereto, metallic tape which binds the conductors and tubes, and a sheath which surrounds the tape and forms a fluid tight closure 70 75 80 for the cable.

3. In an electric cable, the combination of a plurality of insulated conductors arranged about a common center, an enclosing sheath, there being a peripheral space between each 85 pair of conductors and the inner wall of the sheath, a flexible metal tube located in each of said spaces and comprising a spirally wound strip of metal, the edges of each turn interlocking with the edges of adjacent turns 90 to prevent deformation, said tubes supplying fluid insulation to the spaces and insulation and also assisting to support the sheath.

4. In an electric cable, the combination of a plurality of sector shaped conductors, a body 95 of insulation for each conductor, a metallic covering for each of said bodies, a flexible metal tube comprising a spirally wound strip of metal having overlapping and interlocking edges which is in mechanical and electrical contact with the metallic covering of adjacent conductors, supplies fluid to the insulating bodies, assists in supporting the sheath in the region between two conductor coverings and transmits heat from the conductors and fluid to the sheath. 100 105

5. In an electric cable, the combination of a plurality of insulated conductors arranged about a common center, tubes located in the spaces between the conductor coverings to 110 supply fluid to the insulation each of which is made of a spirally wrapped strip of metal, each of the turns of said strip having an arched portion and edges which interlock with the edges of adjacent turns to prevent 115 deformation, a metal tape which binds the parts together and rests on the insulated conductors and also on the metal tubes, and an enclosing sheath.

In witness whereof, I have hereunto set my 120 hand this 23rd day of August, 1928.

WILLIAM C. HAYMAN.
